UNITED STATES PATENT OFFICE.

MAX SKLOVSKY, OF MOLINE, ILLINOIS, ASSIGNOR TO DEERE & COMPANY, OF MOLINE, ILLINOIS, A CORPORATION OF ILLINOIS.

HEATING FURNACE.

Application filed July 21, 1921. Serial No. 486,505.

My invention relates to heating furnaces in which liquid fuel is used, and has particularly to do with furnaces of the type shown and described in my application, Serial No. 5 367,152, filed March 19, 1920, Patent Number 1,591,891, in which fuel oil is carried into the combustion chamber of the furnace through the agency of a stream of air under pressure passing through a Venturi nozzle 10 to which the oil is supplied. The result is that the oil in the form of a fine mist intimately mixed with air is injected into the combustion chamber.

In furnaces of this type the amount of fuel required depends to some extent upon the nature of the work that is being done by the furnace, or the conditions under which it is being operated, and, therefore, in order that air and oil may be delivered to the combustion chamber in proper proportions to secure the best results under all conditions, it is desirable that means be provided for varying the volume of air supplied as well as the quantity of fuel oil, but as the breaking up of the fuel oil delivered by the Venturi nozzle into a fine mist preliminarily to its subsequent vaporization in the combustion chamber depends upon the velocity of the air at the point in the nozzle where it takes up the oil, it is of vital importance that any variation of the volume of the air supplied be effected without materially affecting the velocity of the air stream at the point where it meets the oil. This will be readily appreciated when it is borne in mind that in a Venturi nozzle like that shown in my said application the fuel oil inlet is located at the smallest diameter of the nozzle in order to utilize the velocity of the air at that point to shear off the oil and break it up into fine particles as it leaves the inlet duct and comes into contact with the stream of air flowing at high velocity. Obviously, therefore, if the volume of air supplied should be regulated by an ordinary valve located in the air line in advance of the Venturi nozzle, decrease of the volume of air supplied would result in a lessening of the velocity of the air, and consequently 50 would lessen its shearing or breaking up effect upon the oil, which would interfere with its proper intermixture with the air, and prevent or retard proper vaporization thereof in the combustion chamber. To 55 avoid this objectionable result and to pro-

vide means by which the volume of air passing through the Venturi nozzle may be regulated as required without varying its effective velocity, by which I mean its velocity at the point where the oil is taken up by 60 the air stream, is the principal object of my present invention. A further object is to provide means for regulating the volume of air in the manner indicated, which will also permit the operator to visually inspect 65 the operation of the apparatus while it is in use, so that he may see whether or not it is operating to the best advantage. In the accompanying drawings I have illustrated my preferred form of apparatus by which these 70 objects may be accomplished, what I regard as new being pointed out in the claims.

In the accompanying drawings,—

Fig. 1 is a vertical section of a furnace such as that shown and described in my 75 said pending application, having the improvements which form the subject-matter of my present application applied thereto;

Fig. 2 is a sectional view of a Venturi nozzle illustrating the valve mechanism by 80 which the volume of air admitted is controlled;

Fig. 3 is a vertical cross-section on line 3—3 of Fig. 2; and

Fig. 4 is a view of the air regulating valve 85 showing part of the operating lever therefor.

Referring to the drawings,—5 indicates a fuel oil consuming furnace, and 6 the combustion chamber thereof. In one of the end 90 walls of the furnace is an opening 7 through which the materials to be heated may be introduced, said opening being arranged to be closed by a door 8. In the construction illustrated, said door is adapted to slide vertically in suitable guides, and is operated by a lever 9 connected therewith by a link 10. 11 indicates an air heater of any suitable description adapted to employ the waste gases of the furnace to heat the air delivered 100 thereto, which is located over a discharge passage 12 at the top of the combustion chamber. 13 indicates an air supply pipe which is connected with a fan or other means of supplying air under pressure, and 105 communicates with the air heater 11. 14 indicates an air pipe which leads from the air heater 11, and supplies air to a Venturi nozzle 15 mounted in the end wall of the furnace opposite that containing the opening 7. 110

As best shown in Fig. 2 the Venturi nozzle 15 is provided at its narrowest point with a circumferential channel 16 which opens into the bore of the nozzle at its narrowest point through a duct or minute orifice 17 located at the upper side of the nozzle. 18 indicates an oil supply pipe which communicates with the channel 16 for supplying oil thereto, said oil supply pipe being provided with a valve 19 at any convenient point for regulating the oil supply. Above the orifice 17 is an opening adapted to be closed by a screw plug 20, through which opening said orifice may be conveniently cleaned when necessary. 21 indicates a diaphragm located in the combustion chamber adjacent to the discharge point of the nozzle 15, and provided with a central passage 22 through which the finely divided mixture of air and oil are introduced into the combustion chamber.

The apparatus as thus far described is substantially the same as that shown and described in my said pending application, and, therefore, it will suffice for present purposes to explain briefly that its purpose is to effect the injection of a mixture of finely divided fuel such as fuel oil and air, either hot or cold, at high velocity into the combustion chamber of the furnace, utilizing the momentum of the incoming air and fuel to cause a circulation in the combustion chamber of the products of previous combustion therein, by which such products of combustion will be brought into intimate association with the incoming fuel mixture before combustion thereof is accomplished. As these products of combustion are very hot, they instantly raise the incoming fuel to a high temperature so that it is gasified and ignited. The intimate association of the highly heated gasified fuel and the air, which are supplied in the proper proportions to effect substantially perfect combustion, together with the circulation of the mixture in the combustion chamber, ensures the complete, perfect, and substantially instantaneous combustion of the fuel without waste, so that very high temperatures can be very quickly obtained.

Coming now to the improvements which form the subject-matter of the present application, and which, as has been explained, have to do principally with the provision of means by which the volume of air supplied may be varied without materially varying the effective velocity of the air stream, 23 indicates an air regulating valve in the form of a plunger, which is preferably tubular, as best shown in Fig. 4. This valve is mounted to slide telescopically in a bearing 24 alined with the axis of the nozzle 15, so that said valve may be moved longitudinally of such axis. As best shown in Figs. 2 and 3, the inner end of the valve 23 is tapered or inclined at its upper side, and its inner

end portion bears upon and is slidably supported by the inner surface of the constricted portion of the nozzle opposite the inlet orifice 17. That portion of the inner wall of the nozzle opposite the inclined portion of the valve 23 is correspondingly inclined, in order that there will not be a restriction in the cross sectional area of the passageway 25, through which the air from the air supply pipe 14, in its course through the nozzle, passes before it reaches the constricted portion of the nozzle wherein the oil inlet orifice 17 is located. Obviously, the area of said passage and its opening in the constricted portion of the nozzle may be increased by moving the valve 23 to the left from the position shown in Fig. 2, or it may be reduced by moving said valve in the opposite direction, and it is evident that by properly varying the size of such opening at the constricted portion of the nozzle it is possible to maintain the stream of air flowing therethrough at a substantially uniform velocity notwithstanding any increase or decrease of the volume of air delivered through the nozzle. By this construction, therefore, the volume of air may be properly regulated to secure the most effective mixture, whether the supply of oil be increased or diminished, without in any manner interfering with its function of atomizing and taking up the oil.

For conveniently adjusting the position of the valve 23, it is provided at its outer end with a collar 26 having pins 27 at its opposite sides. These pins operate in slots 28 in an operating lever 29 having an intermediate yoke 30 between the members of which the collar 26 is fitted. Preferably, the lever 29 is fulcrumed on a pivot 31 mounted on a bracket 32 carried by the nozzle 15, as shown in Fig. 2.

As has been suggested, the valve 23 is preferably tubular, the object of which construction is to permit the operator to visually inspect the oil feed. In furtherance of this object the inner end of the valve 23 is provided with a plug 23^a tapered to conform to the taper of the valve, and provided with a longitudinal passage 33 giving a view of the oil feed. The outer end of the valve 23 is closed by a window 34 of mica or other suitable transparent material, which is fitted over the end of the valve and is held in place by the collar 26, as shown in Fig. 4. By this means the observer, by looking through the window 34, may see whether or not the oil is being properly dropped into the nozzle and atomized by the air stream.

So far as I am aware, I am the first in the art to provide a fuel oil consuming furnace employing a high velocity stream of air to deliver the oil to the combustion chamber, with means by which the volume of air may be regulated without materially altering the effective velocity of the air, and,

therefore, the claims hereafter made are to be construed generically, except in so far as they may be directed to specific features of the construction shown and described.

5 The term "oil" as herein used is intended to include any and all suitable liquid fuels, and by the term "compressed air" I mean any suitable gas supplied at a velocity high enough to properly effect the delivery of

10 the fuel.

What I claim as my invention and desire to secure by Letters Patent, is—

1. A spray burner comprising a Venturi nozzle, means for supplying air under pressure to said nozzle, means for admitting fuel oil to the air stream flowing through said nozzle at the constricted portion thereof, a manually-operable valve movable into and contacting with the inner surface of the nozzle at the constricted portion thereof opposite the point of admission of the oil into said nozzle to vary the area of the air passage therethrough, and means operable to adjust the position of said valve.

2. A spray burner comprising a Venturi nozzle, means for supplying air under pressure to said nozzle, means for admitting fuel oil to the air stream flowing through said nozzle at the constricted portion thereof, a manually-operable tubular valve supported by and movable into the constricted portion of said nozzle adjacent to the point of admission of the oil thereto to vary the area of the air passage therethrough, and means operable to adjust the position of said valve.

3. A spray burner comprising a Venturi nozzle, means for supplying air under pressure to said nozzle, means for admitting fuel oil to the air stream flowing through said nozzle at the constricted portion thereof, a manually-operable valve having a tapered inner portion movable into and contacting with the constricted portion of said nozzle, and cooperating therewith to vary the area of the air passage therethrough adjacent to the point of admission of the oil and means operable to move said valve.

4. A spray burner comprising a Venturi nozzle, means for supplying air under pressure to said nozzle, means for admitting fuel oil to the air stream flowing through said nozzle at the constricted portion thereof, a manually-operable valve telescopically mounted in said nozzle, one end portion of said valve being mounted in and extending

outside of said nozzle and the other end portion thereof being tapered, the tapered portion of said valve being movable into the constricted portion of said nozzle for varying the area of the air passage therethrough and means operable to move said valve.

5. A spray burner comprising a Venturi nozzle, means for supplying air under pressure to said nozzle, means for admitting fuel oil to the air stream flowing through said nozzle at the constricted portion thereof, and a manually-operable valve telescopically mounted in said nozzle, one end portion of said valve extending outside of said nozzle and the other end portion thereof being slidably supported by and movable relatively to the constricted portion of said nozzle to vary the area of the air passage therethrough adjacent to the point of admission of the oil.

6. A spray burner comprising a Venturi nozzle, means for supplying air under pressure to said nozzle, means for admitting fuel oil to the air stream flowing through said nozzle at the constricted portion thereof, a manually-operable valve telescopically mounted in said nozzle co-axially therewith and movable relatively to the constricted portion thereof to vary the area of the air passage therethrough, said valve having a sight passage therethrough for observing the oil feed, and a window fitted in said passage.

7. A spray burner comprising a Venturi nozzle, means for supplying oil to said nozzle, means for supplying air under pressure to said nozzle, a valve having a sight passage therethrough for observing the oil feed, said valve being movable into the constricted portion of said nozzle adjacent to the point of admission of the oil thereto, for varying the area of air passage through said nozzle, and a window fitted in said passage.

8. A Venturi nozzle having a constricted air passage, an oil inlet opening laterally into said air passage, and a valve mounted telescopically in the nozzle and movable longitudinally of the axis thereof for varying the area of such constricted air passage, one end of said valve extending outside of the nozzle and the other end thereof being slidably supported on the inner surface of the nozzle at the constricted portion thereof.

MAX SKLOVSKY.
